UNITED STATES PATENT OFFICE

LOTHAR MAGER, OF HEIDELBERG, GERMANY, ASSIGNOR TO SCHNELLBETT GESELLSCHAFT MIT BESCHRÄNKTER HAFTUNG, OF HEIDELBERG, GERMANY

FOLDING BED

Application filed March 16, 1929, Serial No. 347,616, and in Germany March 24, 1928.

The invention relates to a folding bed which differs from known beds of this class therein, that two longitudinal supporting members and two transverse supporting members, lying loosely and over one another, are connected with four corner posts or legs, and that a strip of fabric is stretched between the longitudinal supporting members or the transverse supporting members 10 in such a manner, that a bedstead is formed without the aid of connecting means of any kind such as bolts, screws, hooks or the like.

By means of this arrangement a folding bed is formed having a comparative light 15 weight and great stability at a very small cost.

It is expedient to provide the longitudinal, as well as the transverse supporting members, on each end, with a shell which can be 20 pushed over the corner posts or legs. These shells may be arranged in such a manner that they project farther over one side of the central axis of the supporting members than on the other side. By this arrangement 25 it is possible to have one end of the fabric positioned higher than the other end.

If the longitudinal supporting members, as well as the transverse supporting members, are each connected with a strip of fabric, these being stretched by the connection 30 with the corner posts or legs, a secure holding of the entire bedstead is attained, and a soft and reliably firm couch is formed.

The corner posts or legs are made of four 35 perfectly equal rods or tubes, they being provided with annular projections, or with lugs, or the like, which are adapted to carry the longitudinal and the transverse supporting members. As the longitudinal supporting 40 members, and also the transverse supporting members, are alike unto each other, it is possible to interchange the respective parts.

In the accompanying drawing the invention 45 is illustrated in one form by way of example, in which Figure 1 is a plan view of the longitudinal supporting members of the bedstead with a strip of fabric fastened thereto; Fig. 2, a plan view of the trans- 50 verse supporting members, to which a strip

of fabric is also fastened; Figure 3, a side elevation of a corner post or leg; Figure 4, a side elevation of the erected bedstead, and Figure 5, an end elevation of the head end of the bedstead.

The two longitudinal supporting members 1 and 1¹, made of tubes in the example shown, but which may have any other cross section, are provided on each end with a shell like member 2, the axis of the latter 55 members being directed vertically in respect to the axis of length of the longitudinal supporting members 1 and 1¹. Furthermore, the shell like members 2 are fastened to the supporting members in such a manner, that 60 they project one-sidedly over the axis of the members 1 and 1¹.

The supporting posts or legs 3, made of tubing or rod-material, are inserted into the shell like members 2. Annular projections 70 4 are provided on the supporting posts or legs 3, these projections serving as stops for the ends of the shell like members 2.

The long sides of the strip of fabric 5 are provided with seams 5¹ so as to form loops 75 into which the longitudinal supporting members 1 and 1¹ are inserted.

The transverse supporting members 6 and 6¹ are provided with shell like members 7 in the same way as the longitudinal supporting members, these members 7 being dimensioned and arranged the same as the shell like members 2. The transverse supporting members are inserted into loops by means of the seams 8 on the short sides of the strip 80 of fabric 8. By pushing the shell like members 7 above the shell like members 2 onto the four corner posts or legs, the entire bedstead is firmly erected, whereby the tensions arising in a transverse direction are carried 85 by the strip of fabric 5, and those arising in a longitudinal direction are carried by the strip of fabric 8.

When pushing the shell like members 7 of the transverse supporting members 6 and 6¹ onto the corner posts or legs it is expedient to do this in that manner, that on one end, the ends of the shell like members 7 which project over the transverse supporting member 6 are turned upward, and on 90 95 100

the other end, at the transverse supporting member 6¹ they are turned downward. The strip of fabric then lies, as shown in Fig. 4, higher on one end than on the other end, 5 so that under certain conditions a pillow is not required.

When the bed is in use, the strip of fabric 8 is pressed down onto the lower strip of fabric 5, so that both strips of fabric 10 carry the load. In case of necessity, warming materials may be inserted loosely between the two strips of fabric, thereby giving a possibility of using the bed in the open air.

15 If a number of beds are to be set up above one another, an intermediate member 9 having sockets on both ends (Fig. 4) is put onto the upper ends of the corner posts 3 which project out over the shell like members 7 20 of the transverse supporting members 6 and 6¹, the lower end of corner post or leg of the upper bed being inserted into the socket 10 of the intermediary member 9.

When folding the bed, as soon as the 25 transverse supporting members 6 and 6¹ with their shell like members 7 are withdrawn from the corner posts or legs, the entire bedstead collapses, and after withdrawing the corner posts or legs 3 out of the shell 30 like members 2 the strips of fabric may be rolled up.

I claim:

A folding bed, comprising longitudinal members, a sleeve-like member provided at 35 each end of said longitudinal supporting members, corner posts, each having a projection, said sleeve-like members being slidably arranged on said corner posts, a strip of fabric loosely connected to said longitudinal 40 supporting members, transverse supporting members each having a sleeve-like member at each end, said sleeve-like members being arranged to project farther beyond the central axes of said transverse supporting members on one side than on the other, the last-named sleeve-like members being slidably 45 arranged on the said corner posts above the first-named said sleeve members and a second strip of fabric loosely connected to said 50 transverse supporting members, said two strips of fabric forming tension members to firmly hold said longitudinal and transverse members in rectangular position.

In testimony whereof I have affixed my 55 signature.

LOTHAR MAGER.
